UNITED STATES PATENT OFFICE.

GEORGE HOWLETT DAVIS, OF NEW YORK, N. Y.

PERFORATING AND RECORDING MACHINE.

SPECIFICATION forming part of Letters Patent No. 659,053, dated October 2, 1900.

Application filed September 2, 1898, serial No. 604,608. (No model.)

To all whom it may concern:

Be it known that I, GEORGE HOWLETT DAVIS, a citizen of the United States, residing at New York, in the county of New York and State of New York, have invented a certain new, useful, and valuable Improvement in Electric Perforating and Recording Machines, of which the following is a full, clear, and exact description.

10 My present invention relates to electric perforating and recording machines, and particularly to that class of perforating-machines designed to perforate music-sheet paper for use with automatic instruments.

15 My invention has for its objects, first, to provide, in connection with the perforating mechanism, means for accurately recording the performance of a pianist and produce paper perforated in exact accordance with the 20 depression of the keys of the piano connected thereto; second, to provide an endless automatic apron-feed for use when a number of 25 thicknesses of paper are being cut or perforated at one time; third, to provide a novel 30 form of contact device for use in reproducing a number of copies from an ordinary perforated sheet or "stencil;" fourth, to provide a new form of electromagnetic mechanism for actuating the draw-bars or dogs; and, fifth, to 35 provide other novel constructions and combinations of parts, such as will be hereinafter described.

I do not claim in the present application the combination with a piano of a perforating- 35 machine with locking device for the punches and means connecting the keys and locking devices for producing a perforated music-sheet simultaneously with the depression of the keys of the piano, as such a combination 40 is claimed in my copending application, Serial No. 630,593, filed August 8, 1899. I have made several previous applications in this class, and perforating-machines built upon designs 45 therein disclosed are now in use; but these and other like machines have more or less serious defects, of which I will recite a few and state how I overcame them.

In perforating-machines now in use for manufacturing perforated music-paper nearly all 50 employ an apron-feed three or four times longer than my present one and the clamps for securing the paper require changing by

hand or the attention of a man, and this changing of clamps usually results in a slight disarrangement of the numerous sheets of paper held thereby, whereas my present apron-feed is extremely small, only eighteen inches in length, is entirely automatic, thus saving the services of a man, and the paper is clamped uniformly by the automatic clamp 55 without danger of disarrangement. In some of these perforating-machines an extremely large and clumsy stencil is required to actuate the dogs—*i. e.*, a special stencil many times thicker, wider, and longer than the reproduced perforated sheet or commercial music-rolls—whereas with my present machine one of these commercial music-rolls can be run through the contact device of my machine and as many as thirty copies reproduced therefrom in each operation, thus saving an immense amount of space, money, and time in making, storing, and handling the special stencils.

In the former machines of my own design 75 a comparatively large amount of electric current was required to properly actuate the magnets, which was otherwise objectionable, because it caused too great a spark upon the stencil, breaking the circuit at the contact device, and because it prevented obtaining a perfect record from the operation of piano-keys connected thereto, owing to the "sticking" of the key-contact at the time of breaking circuit, whereas with my present magnets 85 fully eight-tenths of the current formerly used is saved and sticking prevented, owing to the current being cut down to almost nothing before the current is broken.

One objection which I have sought to overcome in the present machine, which has been found in some of the perforators now in use, was the wearing of the cutting edges of the punches. This was occasioned by the wear of the reciprocating punch-plate in its guides, 95 which permitted the punches to get slightly out of register with the holes in the die-block, over which the paper was fed, so that the punches rapidly wore by contact with the block. In the present machine the lower 100 ends of the punches are accurately guided to the holes in the die-block independently of any wear of the punch-carrying frame in its guides, and in my present machine the ragged

cutting heretofore resulting from the above causes is entirely overcome, enabling my machine to cut clean for a much longer time than in any machine heretofore used.

5 In the accompanying drawings, Figure 1 is a side elevation of my complete machine. Fig. 2 is an enlarged transverse sectional view of my contact device. Fig. 3 shows a transverse section of the left-hand half of the machine. Fig. 4 is a longitudinal section of the endless automatic apron-feed. Fig. 5 is an end view of same. Fig. 6 is a transverse section of a cross clamp-plate. Fig. 7 is a view of the bottom of one end of a top clamp-piece. Fig. 8 is a detail view, partly in section, of my "economy magnet." Fig. 9 is a detail plan view of my rack-making mechanism.

Proceeding with a detailed description of my invention, I will first take up my punch and die mechanism and its operating mechanism. (See Fig. 3.) The former consists, primarily, of the die-plate 1, in which is made a series of holes 2 and rigidly secured to the bed 3. Said holes 2 are enlarged or reamed out at the bottom and lie over a slot 5, made in said bed 3, and through which the punchings or waste fall. The lower part of the die-block 6 is rigidly secured at either end to said die-plate 1, so as to leave a narrow space or slot 7 between it and the die-plate 1. The lower end of each punch 8 rests in one of the holes made through the lower die-block 6, and its upper end passes through the upper punch-plate 9, and its cap 10 normally rests upon the bottom of the slot 11, made in said upper punch-plate, which latter is secured to the bottom of the frame 12, itself attached to the slide-blocks 13 and reciprocated by the pitman-arms 14, pivotally secured to said slide-blocks at their lower ends and given motion by the eccentrics 15, rigidly secured to the shaft 16, which is revolved from any suitable motive power. Resting in horizontal slots made in said frame 12 are a series of draw-bars or dogs 17, having centrally-located recesses 18, which normally stand over the tops or caps 11 of the punches 8. The rear end of said recesses 18 are beveled, as shown, and to the front ends 5c of said dogs are hooked the looped ends of the rods 19, extending to and adjustably secured to the lower ends of the armatures 20, the latter being hinged upon the cleats 21, as shown.

55 The main magnets 22 are peculiarly wound and constructed, as clearly shown in Fig. 8, where one of the magnet-coils is shown in section, it being understood, of course, that the other coil is similarly wound, their novel features consisting mainly of compound-wound spools, one winding being of large wire 23 and the other of comparatively fine wire 24, the latter so wound as to occupy the spaces left between the larger wires, as shown in Fig. 8, and acts as a resistance and greatly reduces the current when thrown into series with the larger wire in any suitable manner.

This is accomplished in this instance by the armature 20 forcing the rod 25 against the contact-spring 26 and separating the latter from the contact-point 27 about the time the armature has completed its movement and is in proximity to the poles or heads of its magnet 22, thereby causing the current to again traverse the magnet through the fine wire 24, 75 as well as through the large wire 23, in order to reach the terminal 28, the short circuit thereto having been interrupted the moment the spring 26 is forced away from the contact 27, as heretofore described. In a perforating-machine the magnets are frequently kept energized for a comparatively long time in order to keep the punch set to produce the long slots in the paper representing sustained notes in music, and with an ordinary magnet the 85 same amount of current would continue to pass through it during its entire period of energization as was required to first attract the armature and set its punch. After the initial movement of the armature little or no power 90 is required to keep the punch set, and therefore the continuation of the maximum current is a great waste of electrical energy, while with my new form of economy-magnets the current is reduced to about one-tenth after 95 the magnet has done its heaviest work or its armature made its initial movement. An immense saving of current is not only thus effected, but the spark at the point of breaking contact is reduced one-tenth, and whether 100 this be at the piano or copying contact device this is a decided advantage and removes several almost fatal objections heretofore existing in the class of machines—i. e., the sticking and burning of contacts on the breaking 105 of a heavy circuit and also running the slots together when recording piano performances, as well as charring the thin paper used as a stencil on the copying device.

In order to produce slots in the paper being 110 perforated which are relatively shorter than the time of contact at the piano-key, I employ the relay-magnets 29 and connect them direct to the piano-key contacts 30 and so adjust the magnet-contact screws 31 32 as to complete 115 the circuit therethrough and through the main magnets 22 practically only when the armature 33 of the relay-magnets is in actual contact with its magnet-heads. The circuit through the main magnet and the set of the 120 punch is only shortened the infinitesimally short time it requires for the armature to move forward; but as the punches must be set or locked and unlocked two thousand two hundred times per minute, which is the speed of 125 revolution found necessary to record piano performances, even such infinitesimal periods of time are appreciable. An important advantage of the relay-magnets also results from their power to make and break the main-line 130 circuits promptly and positively, whereas it would be impracticable to change the touch of a piano-key 34 sufficiently to do this. When my economy-magnets are employed on

the main circuits, the use of the relay-magnets is not so essential as when ordinary magnets are used, for the reason that the economy-magnets, as stated above, so reduce the current flowing through the punch setting and holding device as to eliminate the danger of sparking under the influence of a heavy current and the objections thereto, and therefore the necessity of the rapid making and breaking of the circuit which the relay gives is not so essential, for the piano-key movement will under these conditions be sufficiently rapid to give movement to the circuit-closing device which cuts into circuit the punch-controlling magnets.

The advantage of securing a perforated sheet with the slots comparatively shorter than the time of the corresponding depression of the piano-keys 34 is that it is very easy to afterward lengthen any slots which may require it, owing to there being plenty of paper or bridge between the slots or notes. If, however, the slots are relatively longer, even to the slightest degree, than the time of corresponding contacts made by the depression of the piano-keys, then the slots run together frequently when a performer trills or rapidly repeats a particular note which would render it necessary to paste strips of paper on the music-sheet to separate all such slots, and this is found impracticable. This running together of the slots is obviated by employing either the relay-magnets on the piano-circuit or my economy-magnets on the main circuits. The economy-magnets obviate a running together of the slots, because at the time the circuit is broken the current through the fine wire is so small or weak as to cause no sticking of the contacts at the time of breaking the circuit, it being well known that when a heavy current is passing through contacts there is a tendency to retard the break, such action being technically called a "stick," and this effect is very apparent with such delicate contacts as are used in this device. If the breaking of contacts is retarded, then necessarily the magnets keep the punch locked longer than required, and thus cause a running together of the slots.

When only one thickness of paper is to be perforated at an operation, as when recording a piano performance or making a trial stencil, I prefer to wind it upon a large supply-spool 35 and lead it between the lower punch-plate 6 and the die-plate 1 and from thence between the lower or live feed-roller 36 and the upper or presser roller 37, which latter is adjusted in any suitable manner to press the single sheet between it and the live roller. Said live roller 36 is revolved by means of a ratchet-wheel 38, engaged by the pawl 39, pivoted upon a branch 40 of the arm 41, said arm being given a reciprocating movement by the connecting-rod 42, working on an eccentric 43, fixed on the shaft 16, and so set as to receive the roller 36 and give the

paper a forward movement of about one-twentieth of an inch at the time the reciprocating frame 12 is raised and the punches are also raised free of the paper. This step-by-step movement continues at the same rapid but uniform rate as the revolution of the shaft 16, a step being made for each revolution, which in recording a piano performance is generally two thousand three hundred times per minute; but in duplicating or manufacturing the speed is reduced to about one thousand revolutions, as sixteen or more sheets are then perforated at each operation and the circuits through the main magnets 22 are then completed through the copying-contact 44. Said contact device 44, which is actuated by the stencil, may be attached to any suitable part of the perforating-machine, as shown at Fig. 1, or it may be located any distance therefrom. It consists of two members, a revolvable contact-roller 45 and a series of metal contact figures or selectors 46, which bear on the roller and are pivoted upon a non-conducting rod 47, all set in and supported by the frame 48, having a slotted bar 49 across its front, in which the selectors rest and are guided or prevented from wabbling at their free ends 50. The contacting ends 95 or surfaces 51 of the selectors 46 are curved, so as to rest perfectly true upon the contact-roller 45, which shape they will assume perfectly after a little wear, and said ends 51 are very carefully cut, so as that they are nearly equal in width to the diameter of the punches 8. The difference between the width of the contact-face 50 of these selectors 46 and the diameter of one of the punches 8 or a single perforation made in the stencil 52 by said punches is generally one-twentieth of an inch, which is the extent of a single step in the stencil-feeding movement, thus practically insuring that the selectors do not miss falling into each and every single perforation and form contact during the time of one step of the stencil 52, but yet makes them too wide to continue contact during two steps of the stencil. The object of making the contacting faces of the selecting-fingers of the width described may be best understood by first imagining their faces to be sharp, like a pin, in which case they would form contact during two or three feed movements of the stencil. Next imagine the contact-faces to be the same width as the diameter of a single punch-hole, in which case there would be no certainty that the face of the finger would be left in contact when the single holes recur unless the stencil was fed by rack-holes. Therefore when the stencil-sheet is fed forward by means such as rollers it is necessary to determine a width for the contact-fingers which will always form contact during one step of the stencil and yet be thrown out of contact by the imperforate portion of the sheet upon the second step. When said stencil is fed forward step by step simply between rollers, such as 45 53, (shown at Fig. 2,) it is impossible to prevent a gain

or loss occasionally between the steps of one-twentieth of an inch given the stencil with only comparative accuracy on the perforating-machine when originally cut and that given it by the presser-rollers of the contact device. The latter would have only to work inaccurately the one one-thousandth part of an inch each step to cause the stencil to lose or gain a step about every four feet, and the stretching or swelling of the paper-stock of the stencil is always sufficient to alone effect this slight inaccuracy which would in actual time only effect a note the one fourteen-hundredth part of a minute once in about every four feet. This would be sufficiently accurate for ordinary purposes, and under this system it would be possible to employ as a stencil any one of the thin paper music-rolls sold for use with such automatic instruments as the aeolian and reproduce therefrom any number of copies, running about sixteen thicknesses of paper through the perforator proper while the single sheet is traveling in unison therewith through the copying contact device. The copying contact device just described is in circuit with the punch-controlling magnets 22, as clearly shown in Fig. 1, and a switch 50' is shown by means of which the circuit through the copying contact device may be broken when the magnets and perforating mechanism are to be operated by the key mechanism 34 of the piano and not through the stencil 52 and its operating mechanism.

In order to avoid the slight inaccuracy between the stencil and the sheets perforated therefrom and produce in the latter identically the same number of perforations as was originally made in the stencil, I make in any suitable manner a series of equidistant holes or racks 54 at either edge of the stencil 52, each of said rack-holes being made exactly in line transversely with the stepped punch-holes or position of punch-holes of the perforator and separated at prearranged intervals. For instance, a rack-hole would be made on either side of the sheet to be used as a stencil at every twelfth step given the sheet in originally perforating it and which is easily detected by the teeth on the edge of the slots left by the punches, by roller-marks, or measurement. Assuming that the rack-holes have been made at either edge of the stencil-sheet, by providing teeth or sprockets 55 on either end of the contact-roller 45 of the contact device, so arranged as to correspond with and engage each of the rack-holes 54 on the stencil-sheet, then when the said roller is revolved, as by the pawl-and-ratchet mechanism 56, (shown in Fig. 1,) so as to advance step by step at a rate equal to that given the paper 57 being perforated, the step-by-step movement of the stencil given by the sprockets 55, engaging its two racks, must exactly correspond with the step-by-step movement originally given it when perforated, and any inaccuracy in said original movement or

inequalities resulting from the shrinking or stretching of the stencil after being first cut will be partaken of and equalized by the racks and sprockets. Now the cutting of the racks by hand on a ready-made stencil-sheet to be used as a stencil would prove an extremely tedious operation, although when once done it would render the sheet a perfect stencil for indefinite use; but by the addition to the perforating-machine of the extremely simple and novel mechanism shown in Figs. 3 and 9 I am enabled to cut perfect racks in any sheet desired by simply moving the handle 58 upward, which instantly gives the rock-shaft 59 a partial turn and lowers the arms 60, fixed to the end thereof, and this through the medium of the connecting-wire 61 allows the pitman 62 to lower at its forward end and cause its slot 63 to be entered and its forward edge engaged by the teeth or sprockets 64, set upon the lower or live feed-roller 36, the upper or pressure roller being thrown out of engagement therewith after the racks have reached said roller 36. The said sprockets 64 are set at such distance apart as to successively engage and each slightly throw forward the pitman 62 about every twelfth step, or three-fifths of an inch apart, said forward movement of the pitman 62 causing a partial revolution of the rock-shaft 65 through the medium of its downwardly-projecting arm 66, to which the pitman is pivotally connected. Near the ends of said rock-shaft 65 and in line with proposed racks 54 are provided two upwardly-projecting arms 67, pivotally connected at their upper ends with two extra draw-bars or dogs 68, which engage and actuate two extra punches (not shown) in identically the same manner as do the intervening dogs actuated by the electromagnets. It is obvious that the rack-holes 54 produced at either edge of the sheet must be absolutely perfect, as they cannot fail to be equidistant and in perfect line with the other punches with which they are lined up and are preferably made duplicates, the distinction being that the two rack-hole punches and dogs are operated by mechanical means, while the other dogs and punches making the note-holes are actuated electrically. It will be apparent that the sprocket-teeth 64 will slip out of the elongated slot 63 in the pitman 62 as the sprocket-roller 36 revolves after it has thrown the rack-punch-actuating mechanism. I also anticipate the electrical actuation of the rack-hole draw-bars 68 and their punches, which could be accomplished by several apparent modifications, one of them being to have the ends or points of the sprockets successively and independently complete an electrical circuit through magnets arranged to actuate the dogs 68 in the same way that they actuate the other dogs 17. I deem mechanical means substantially as herein shown preferable.

When it is not desired to cut rack-holes, the mechanism therefor may be instantly

thrown out of action by simply moving the handle 68 up into its original position.

Up to this time I have dealt with the perforation of a single sheet and giving it a step-by-step forward movement by passing it between the two feed-rollers 36 37, which I hold is the best method of feeding a single sheet; but in manufacturing duplicates, in which case the perforator is under control of the copying contact device and the stencil or copy passing therethrough, it is preferable to reduce the speed of both apparatuses to about one thousand steps per minute and run sixteen or twenty thicknesses of paper through the perforator. It is only in this event that I have found the feed-rollers to occasionally allow some one or more of the sixteen sheets fed thereby to work out of line with the others, and I was therefore led to conceive the endless apron feed shown in Figs. 1 and 4 to 7, inclusive. Said endless apron feed 69 consists of two pairs of endless sprocket-chains 70 71, each pair riding upon four sprocket-wheels 72 73, each pair of wheels supported by separate shafts 75 76, the rear shafts of each pair being forced to revolve in unison by their meshing gears 77 78, rigid with said shafts. Upon the upper rear shaft is secured the large ratchet-wheel 79, engaged by the pawl 80, pivoted upon the slotted arm 81, and both given a slight motion by the pitman 82 sufficient to cause the pawl to revolve the ratchet-wheel one tooth at each reciprocation of the pitman 82, itself taking movement from the main shaft 16 of the perforator. Connecting the two parallel lower sprocket-chains 70 are four equidistant cross-plates 83, with end pieces 84 and provided at each end with two outwardly-extending lugs 85, which engage and slide in correspondingly-arranged slots 86, made in the elevated chain-plates 87, which parts normally or when the chains are straight assume the positions shown in Fig. 4; but when they curve in passing around the sprockets the distance between the slots 86 is slightly decreased and the lugs 85, rigidly located, slide to the farther ends of the said slots and permit the curving of the chains. Said cross-plates 83 are further provided at each end with two rollers 88, which ride upon the tracks 89 90 of the channel-iron 91, and thereby prevent the great friction which would otherwise result when the paper is clamped between the upper and lower plates and propelled forward thereby. Upon the upper chains 70 are arranged cross-plates similar to those just described, but each of which is surmounted by the spring-plates 89', having pins 90' secured thereto and working through the cross-plates 84, said pins 90' being incased by the springs 91, which serve to normally keep the spring-plates 89' at their maximum distance of separation from their cross-plates 83 at all times when not engaged with the said cross-plates 83 of the lower chains 71 in clamping the paper 92. This engagement

or clamping of the paper occurs whenever said plates successively reach and enter the channel-iron 91, whereupon the spring-plate 89' of the upper chains is slightly compressed 70 when it enters said channel-iron simultaneously with its cross plate of the lower chains; but the intervening paper is clamped with sufficient force between the two plates to cause it to be carried forward with the step-by-step movement given the chains by the pawl-and-ratchet action heretofore described, it being obvious that one pair of clamping-plates do not free themselves in passing out of the end of the channel-iron 91 until the 80 following pair have taken hold or clamped the paper. To the forward edges of the upper cross-plates 83 and at either end thereof I show guides 93, which are adjusted to guide the edges of the paper and prevent the numerous thicknesses thereof from getting uneven at their edges. 85

Modifications or changes other than those herein specified may be made without avoiding the spirit of my invention. 90

What I claim is—

1. In a perforating-machine the combination with a driving-shaft, a series of punches, a series of punch setting and controlling dogs, electrical circuits and electromagnets for actuating said dogs, a series of circuit-selectors, a stencil which actuates said circuit-selectors, a die-block over which the material to be perforated is fed, and means for producing a relative reciprocation between 100 the punches and die-block, substantially as described. 95

2. In a perforating-machine the combination with a constantly-driven shaft of a series of punches, a series of punch setting and 105 controlling dogs, electric circuits and electromagnets for actuating said dogs, an electric contact device in said circuits comprising two members, a stencil which passes between the members of said device and means for feeding the material to be perforated beneath the punches, substantially as described. 110

3. In a perforating-machine the combination with a constantly-driven shaft, a series of punches, a die-block means for producing 115 a relative reciprocation between the punches and die-block, a series of punch setting and controlling dogs, electric circuits and electromagnets for actuating said dogs, an electrical contact device in said circuits comprising two 120 members, a stencil which passes between the members of said device and means for feeding the material to be perforated beneath the punches, substantially as described. 125

4. In a perforating-machine the combination with a reciprocating frame of a series of punches mounted to reciprocate in said frame, a series of punch setting and controlling dogs, electric circuits and electromagnets for actuating said dogs, an electric contact device in 130 said circuits comprising two members, a stencil which passes between the members of said

device and means for feeding the material to be perforated beneath the punches, substantially as described.

5. In a perforating-machine the combination with a constantly-driven shaft, a frame reciprocated thereby, a series of punches mounted in said frame, a series of punch setting and controlling dogs, electric circuits and electromagnets for actuating said dogs, 10 an electric contact device in said circuits comprising two members, a stencil which passes between the members of said device, a die-plate and die-block and means for feeding the material to be perforated between said plate 15 and block substantially as described.

6. In a perforating-machine the combination with a driving-shaft of a frame reciprocated by said shaft, a series of punches mounted in said frame, a series of punch setting and controlling dogs carried by said frame, electrical circuits and electromagnets for actuating said dogs so as to throw them in operative relation to said punches, a series of circuit-selectors, a stencil which engages and actuates said circuit-selectors and a die-block over which the material to be perforated is fed, substantially as described.

7. In a perforating-machine the combination with a driving-shaft of a frame reciprocated by said shaft, a series of punches mounted in said frame, a series of punch setting and controlling dogs carried by said frame, electrical circuits and electromagnets for actuating said dogs, a roller, a series of 30 selectors coöperating with said roller, a stencil passing between the selectors and roller and means for feeding the material to be perforated beneath said punches, substantially as described.

40 8. In a perforating-machine, the combination with a driving-shaft, of a series of perforating-punches, a series of punch setting and locking devices to render said perforating-punches operative, means for controlling the action of said setting and locking devices, feeding mechanism to drive the paper beneath the punches, auxiliary rack-forming punches operated from said driving-shaft, and connections between the paper-feeding 45 mechanism and said auxiliary punch mechanism whereby the latter mechanism may be rendered operative when desired to form a rack in the edges of the sheet.

55 9. In a perforating-machine, the combination with a driving-shaft, of a series of punches operated thereby, a series of punch-controlling dogs in operative relation to said punches, means for controlling the action of said dogs, auxiliary rack-forming punches, dogs for controlling said last-named punches, a pair of paper-feeding rollers, one of which is provided with a rack-wheel, connections between said rack-wheel and the auxiliary punch-controlling dogs to actuate the latter, and means for 60 throwing said rack-wheel connections into and out of action as desired.

65 10. In a perforating-machine, the combina-

tion with a driving-shaft, of a series of punches operated thereby, a series of punch-controlling dogs in operative relation to said punches, 70 electrical means for controlling the action of said dogs, auxiliary rack-forming punches, dogs for controlling the said last-named punches, a pair of paper-feeding rollers, one of which is provided with a rack-wheel, connections between said rack-wheel and the auxiliary punch-controlling dogs to actuate the latter, and means for throwing said rack-wheel connections into and out of action as 75 desired.

11. In a perforating-machine, the combination with a series of punches, of means for operating said punches, a series of electromagnets to control said punches, spark-reducing means and piano-key mechanism with which said magnets are in circuit, a copy-holder having a contact-roller over which the stencil passes in circuit with said punch-controlling magnets, means for feeding said stencil, a series of selectors which enter the perforations 85 in the stencil and complete the circuit through the contact-roller, a switch to throw the circuit through the piano-key mechanism or the copy-holder as desired, and paper-feeding mechanism to carry the sheets to be perforated beneath the punches.

12. In an electrical perforating-machine, the combination with the punch mechanism, of a series of electromagnets to control the action of said punches, and a copy-holder 10 having a contact-roller in circuit with said magnets over which the stencil passes, means for giving the stencil a step-by-step feeding movement, a series of selectors having curved faces which rest upon said contact-roller and complete the circuit through the punch-controlling magnets, said selectors being of approximately the same width as the punch perforations in the stencil less the length of a single step-feeding movement of the stencil, 110 and means for feeding the paper beneath the punches.

13. In a perforating-machine, the combination with the punches and their operating mechanism, of paper-feeding mechanism comprising two endless aprons moving in proximity to each other, a series of clamping-plates movable to and from the surface of said apron carried by one of said aprons, a series of plates carried by the other apron with which said movable plates coöperate, and means for imparting an intermittent feeding movement to said aprons.

14. In a perforating-machine, the combination with the punches and their operating mechanism, of paper-feeding mechanism comprising two endless aprons moving in proximity to each other, a series of spring-pressed clamping-plates carried by one of said aprons, a series of rigid plates carried by the other 120 apron, and means for imparting an intermittent feeding movement to said aprons.

15. In an electrical perforating-machine the combination with the punches of a series of

circuits and electromagnets to control the selection of said punches, primary windings for said magnets, circuit-closing devices, spark-reducing means to reduce the sparking at the 5 circuit-closing devices and means whereby the spark-reducing means are rendered operative when the circuit-closing devices are opened, substantially as described.

16. In an electrical perforating - machine 10 the combination with the punches of a series of circuits and electromagnets to control the selection of said punches, primary windings for said magnets, circuit-closing devices, spark-reducing means arranged to be thrown in circuit 15 with said circuit-closing devices to reduce the sparking at the latter, and means whereby the spark-reducing means are cut into circuit after the initial action of said primary windings to reduce the sparking when 20 the circuit-closing devices are opened substantially as described.

17. In an electrical perforating - machine the combination with the punches of a series of 25 circuits and electromagnets to control the selection of said punches, primary windings for said magnets, circuit-closing devices, spark-reducing means arranged to be thrown in series with said circuit - closing devices and means whereby the spark-reducing means are 30 cut in series after the initial action of said primary windings to reduce the sparking when the circuit-closing devices are opened substantially as described.

18. In an electrical perforating - machine 35 the combination with the punches of a series of circuits and electromagnets to control the selection of said punches, primary windings for said magnets, circuit-closing devices, resistances arranged to be thrown in series with 40 said circuit-closing devices and means whereby the resistances are cut into circuit after the initial action of said primary windings to decrease the flow of current through said magnets substantially as described.

45 19. In an electrical perforating-machine the combination with the punches and their operating mechanism of a series of circuits and electromagnets to control the action of said punches, primary windings for said magnets 50 arranged to actuate the punch-controlling devices when energized, electrical resistances and means whereby the resistances are cut into circuit after the initial action of said primary windings to decrease the flow of current to the magnets, substantially as described.

55 20. In an electrical perforating - machine the combination with the punches, of a series of circuits, electromagnets and circuit-closing devices to control the action of said punches, 60 primary windings for said magnets, electrical resistances and means whereby the resistances are thrown into series with the primary windings and the circuit-closing devices after the initial action of said primary windings to 65 prevent sparking, substantially as described:

21. In an electrical perforating-machine,

the combination with the punches, a series of punch-selectors, a series of electromagnets to control the action of said punch-selectors, a series of circuits including contact devices 70 for energizing said magnets, a stencil and spark-reducing means for reducing the spark at the contacts at the time the contacts are opened by the stencil, substantially as described.

75 22. In an electrical perforating - machine the combination with the punches of a series of electromagnets to control the action of said punches, electrical resistances and means whereby the resistances are cut into circuit 80 after the initial action of said magnets to decrease the flow of current through said magnets, a stencil and a series of contact devices in circuit with said magnets, substantially as described.

85 23. In an electrical perforating-machine, the combination with the punches, a series of punch-selectors, a series of electromagnets to control the action of said punch-selectors, a series of circuits including contact devices 90 for energizing said magnets, a stencil and means for reducing the spark at said contact devices, substantially as described.

95 24. In an electrical perforating- machine the combination with the punches, a series of punch-selectors, a series of electromagnets to control the action of said punch-selectors, a series of circuits including contact devices for energizing said magnets, a stencil and means for reducing the currents in said 100 circuits at the time the contact devices are opened by the stencil to reduce the spark at the contacts, substantially as described.

105 25. In an electrical perforating - machine the combination with the punches, of a series 110 of electromagnets to control the action of said punches, of current - reducing devices arranged to be thrown in circuit with the winding of said magnets and means whereby the current-reducing devices are cut into circuit 115 after the initial action of said magnets to decrease the flow of current through said magnets, a stencil and a series of contact devices in circuit with said magnets, substantially as described.

120 26. In an electrical perforating - machine the combination with the punches of a series of electromagnets to control the action of said punches, electric resistances, means whereby the resistances are cut into circuit after the initial action of said magnets, to decrease the flow of current to the magnets, a stencil and a series of contact devices in series with said magnets.

125 27. In an electrical perforating - machine the combination with the punches of a series of electromagnets to control the action of said punches, electrical resistances arranged to be thrown in series with the winding of the magnets, means whereby the resistances are cut 130 into circuit after the initial action of said magnets to decrease the flow of current through

the magnets, a stencil and a series of contact devices in series with said magnets, substantially as described.

28. In an electrical perforating-machine, 5 the combination with the punches and their operating mechanism, of a series of electromagnets to control the action of said punches, said magnets having a primary and secondary winding, the former winding being arranged 10 to actuate the punch-controlling devices when energized, and means whereby the secondary winding is cut into circuit after the initial action of said primary winding to increase the 15 resistance of the coil and decrease the flow of current to the electromagnets.

29. In an electrical perforating-machine, 20 the combination with the punches and their operating mechanism, of a series of punch-controlling devices, magnets for actuating 25 said punch-controllers, said magnets being provided with primary and secondary windings, said secondary winding being of finer wire than the primary winding and lying beneath the convolutions of the latter, and 30 means operated by the armature when actuated by the completion of the circuit through the primary winding to cut the secondary winding into series with said primary winding and increase the resistance through the 35 coil and reduce the current flowing to the magnets.

30. In an electrical perforating-machine, 35 the combination with the perforating-punches, of operating mechanism for said punches, paper-feeding devices to carry the paper beneath the punches, a series of primary magnets for controlling the action of said punches, a series of relay-magnets which control the circuits through said primary

magnets, and key mechanism in circuit with 40 said relay-magnets.

31. In an electrical perforating-machine, 45 the combination with a series of perforating-punches, of means for operating said punches, paper-feeding devices to carry the paper beneath 50 said punches, a series of punch-actuating dogs to bring said punches into action, primary magnets controlling said punch-actuating dogs, a series of relay-magnets which control the circuits through said primary 55 magnets, and key mechanism in circuit with said relay-magnets, by the action of which 60 said relay-magnets are energized.

32. In an electrical perforating-machine, 55 the combination with a series of perforating-punches, of means for operating said punches, paper-feeding devices to carry the paper beneath 60 said punches, a series of punch-actuating dogs to bring said punches into action, primary magnets controlling said punch-actuating dogs, a series of relay-magnets which 65 control the circuits through said primary magnets, key mechanism in circuit with said relay-magnets, by the action of which 70 said relay-magnets are energized, a copy-holder having a contact-roller over which a stencil passes, a series of selectors or contact-fingers resting on said contact-roller and in circuit with said relay-magnets, and a switch to throw the current through the key mechanism or the contact-roller as desired.

In testimony whereof I affix my signature in presence of two witnesses.

GEORGE HOWLETT DAVIS.

Witnesses:

FREDERICK C. ALDEN,
LOUIS BERNSTEIN.
